MACHINE FOR PREPARING DRIVE CHAINS FOR SHIPMENT.

No. 443,303.

Patented Dec. 23, 1890.

UNITED STATES PATENT OFFICE.

JAMES DOUGLAS STORIE, OF OSHAWA, ONTARIO, CANADA.

MACHINE FOR PREPARING DRIVE-CHAINS FOR SHIPMENT.

SPECIFICATION forming part of Letters Patent No. 443,303, dated December 23, 1890.

Original application filed October 21, 1889, Serial No. 327,732. Divided and this application filed February 18, 1890. Serial No. 340,952. (No model.)

To all whom it may concern:

Be it known that I, JAMES DOUGLAS STORIE, of the town of Oshawa, in the county and Province of Ontario, Canada, have invented 5 a certain new and useful Improved Machine for Preparing Drive-Chains for Shipment; and I do hereby declare that the following is a full, clear, and exact description of the same.

10 This invention is intended to provide a simple and effective means of dividing up the long lengths of chain kept in store in coils into smaller lengths, in which such chain is usually purchased, and of winding the same 15 into compact coils for shipment.

The measuring devices consist of a spindle, upon which the large coil is mounted and can be rotated, and a number of pins at a distance from the spindle, in connection with a table 20 (preferably having marked on its surface scale-divisions corresponding to the different sizes of links in different chains) on which the smaller lengths will lie, the end of the large coil being drawn to one of the pins and any 25 specified length in links of the portion of chain thus unwound disconnected from the main length. For compactly winding the lengths thus measured off, an adjustable yielding-resistance device operates, in connection 30 with a winding-key similar to that shown and claimed in a contemporary application, Serial No. 327,732, filed October 21, 1889, for Letters Patent, and now pending, of which application this present one is a divisional part, such key 35 consisting of a vertical spindle having a head-piece that projects through an opening in the table, and which also has a vertical slit in it to receive the end link of the chain, and has its sides configurated to suit the shape of the center of the coil formed by the straight surfaces of, say, the first three or four links encircling it, the shape being approximately quadrangular. For full comprehension, however, of the invention reference must be had to the 40 annexed drawings, in which—

45 Figure 1 is a plan view of the machine, a coil of chain being indicated on the spindle by dotted lines; Fig. 2, a similar view showing a length measured off; Fig. 3, a front view 50 of machine. Fig. 4 is a view of part of under side of table; Fig. 5, a vertical cross-sec-

tion of machine; Figs. 6 and 7, details of parts of yielding-resistance device; Fig. 8, a detail showing winding key or spindle depressed below the level of the table, and Fig. 9 an enlarged detail of head of said spindle.

Like symbols indicate corresponding parts.

A is the table, suitably supported by legs A' and having openings a¹ a², an aperture a³, and slot u in its surface.

60 T is a horizontal bar or spindle projecting at a convenient height across the table from a support T', situated about centrally of the machine and at the rear thereof, and t t are pins arranged at the right-hand end of the 65 table.

To measure the lengths of chain from the large coil in store, this coil is slipped onto the spindle T, and according to the length of its links corresponding with one of the scale-divisions marked on the table it will be pushed along the spindle into line with such particular scale. The operator now takes the outer end link of the coil and unwinds (by 70 pulling and so rotating the coil) till he is enabled to fit such link over the pin at the end of the scale, and this being done he detaches the portion at the desired point indicated by the scale.

75 As will readily be seen, the measurements 80 are not confined to small lengths, as an entire coil could be measured by unwinding the coil in portions the full length of the particular scale and keeping count of the number of measurements made, the measured portion of 85 the chain being allowed to fall over the end of the table. This, however, is very seldom required to be done. Of course it is not necessary to have the scale-divisions marked permanently on the surface of the table, as the 90 operator could simply count any desired number of links backward from the end one fitted on a pin, make a chalk mark on the table at the required point, and then proceed to measure off a number of lengths without further 95 counting.

Having disconnected the short lengths required, as before described, it now remains to 100 rewind them into separate coils as compactly as possible for shipment, and to do this the winding and yielding resistance mechanism now to be described is used. The winding

mechanism consists of a key or spindle made up of a head-piece J to project through the aperture a^3 in the table and above the surface of the same while winding, having a slit 5 j in it, as shown in Fig. 9, to receive the end link, and its sides configurated to suit the shape of the center of the coil formed by the straight surfaces of, say, the first three or four links encircling it, the shape being approximately quadrangular. For different sizes of links different-sized heads with same configuration must of course be used, and, as shown in Fig. 5, the arrangement is such that they can be screwed into the top of the 10 plunger, preferably formed in two parts J' J^2 , screwed together, of the spindle. The plunger rests on a spring J^3 , confined within a sleeve J^4 , which carries the pulley H^3 , encircles the plunger and serves to rotate it 15 through a pin J^7 , projecting from the same into a slot j^3 in the sleeve, this slot also serving to regulate the upward movement of the plunger. The spindle secures a vertical bearing in a recessed foot-plate for the end of the 20 sleeve J^4 and a boss on the under side of table A for the upper part J' of the plunger.

J^5 is a lever pivoted at j^3 to a hanger from the table A , slotted to encircle the part J' of the plunger and bearing when it is desired to 25 depress same upon a collar J^6 , secured beneath it to the part J' . This spindle will be rotated by a band from any convenient shafting to pulley H^3 and under control of clutch mechanism, with which lever Q can be connected.

The mechanism for compacting the coil as it is wound consists of a roller X' , mounted on a vertical spindle U , which projects up through slot u in the table from a slide U' , 30 having bearings in guideways on the under side of the table. The function of this roller in connection with such slide is to furnish a yielding pressure upon the coil while being wound, and I have shown a means of effecting such a pressure and of regulating the extent of its application.

U^2 are what may be termed "whiffletrees" or "frames," (shown in front elevation and section in Figs. 6 and 7,) to which and to the 35 slide U' are connected the ends of strong retractile springs U^3 . These frames are pivotally connected by screws u' with nuts U^4 , arranged to travel on adjusting-screws U^5 , carried in suitable bearings, and provided 45 with crank-handles operated through the openings $a' a^2$.

When a chain of very small length is to be wound, the roller X' will of course need to be brought at the start in close proximity to the 50 winding-key, and when a longer one it will be moved farther away.

There is no other connection between the whiffletrees movable by the adjusting-screws and the slide than the springs U^2 ; but their 55 retractile force is such as to condense their coiling to a stability sufficiently rigid to impel the slide and roller in a direction from

the key, when desired, without collapsing in the smallest degree. It will now be seen that when the roller X' is properly located 70 and the length of chain turned up on edge with one end link inserted in the slit j the machine is started and the chain wound around the key, receiving at the same time the pressure of the roller, which increases as 75 the end approaches. As each coil is finished the lever J^5 is depressed so as to lower the head-piece J beneath the table-surface, and so free coil, which is removed, and has its outer end secured in the usual way, leaving 80 it ready for shipment.

What I claim is as follows:

1. In a machine for preparing drive-chains for shipment, the combination, with a table, of a support for a coil of chain from which the same can be unwound, scale-indicators 85 for measuring lengths of chain, a rotating key with means for operating same, and a yielding-pressure device whereby such lengths of chain can be compactly wound into coils. 90

2. In a machine for preparing drive-chains for shipment, the combination, with a table, of a spindle suitably supported, on which a coil of chain can be placed and rotated, one or more pins projecting from said table at a 95 distance from such spindle, and means for indicating the point of detachment of portions of the chain from its coil, for the purpose described.

3. In a machine for preparing drive-chains for shipment, the combination, with a table, of a horizontal spindle suitably supported so as to extend at a convenient height across same, one or more pins projecting from such table at a distance from such spindle, and one 105 or more scale-divisions marked on the surface of the table between said pins and a point beneath the spindle, for the purposes described.

4. The combination, with table A , spindle T , and its support, of pins $t t$, as shown and described.

5. In a machine for preparing drive-chains for shipment, the combination, with a table, of a key or spindle to which the end link is 115 connected and upon which the chain is wound, means for operating such key, and a yielding roller or shoe bearing against the coil and imparting friction thereto, for the purposes set forth.

6. In a machine for preparing drive-chains for shipment, the combination, with a table, of a key or spindle for winding the chain into a coil, means for operating such key, a yielding roller or shoe bearing against such coil 125 and imparting friction thereto, and means for regulating the extent of such frictional pressure, all as and for the purposes set forth.

7. In a machine for preparing drive-chains for shipment, the combination, with table A , provided with slot u , and with means for winding the chain, of slide U' , roller X' , carried thereby, whiffletrees U^2 , springs U^3 , and means for adjusting said slide and roller with

relation to the device for winding the chain, as and for the purposes set forth.

8. In a machine for treating drive-chains, the combination, with a table on which the chain rests edge upward, of a key or spindle projecting above the surface of such table and to which the end link is connected and upon which the chain is wound, such key or spindle being adapted to be withdrawn from the coil and leave the latter intact upon the table, and means for operating such key.

9. In a machine for treating drive-chains, the combination, with table A, on which the chain rests edge upward, and suitable bear-

ings, of a vertical plunger, a head-piece J, 15 adapted to be carried by same, a spring arranged beneath and exerting a pressure on such plunger, a sleeve encircling both the plunger and the spring, means for connecting said plunger with said sleeve, means for 20 rotating said sleeve, and means for depressing said plunger, as and for the purpose set forth.
